UNITED STATES PATENT OFFICE.

WILLIAM H. JOHNSON, OF TERRE HAUTE, INDIANA.

APPARATUS FOR AGING WHISKY.

No. 864,896.

Specification of Letters Patent.

Patented Sept. 3, 1907.

Application filed November 2, 1906. Serial No. 341,719.

To all whom it may concern:

Be it known that I, WILLIAM H. JOHNSON, residing in Terre Haute, in the county of Vigo and State of Indiana, have invented new and useful Improvements 5 in Apparatus for Aging Whisky, of which the following is a description, reference being had to the accompanying drawings, which are a part of this specification.

My invention has relation to improvements in apparatus for aging whisky.

10 The primary object of the invention is to provide an improved apparatus adapted for causing the circulation of heat evenly through the receptacle containing the whisky, permitting the gradual heating of the contents until every particle is raised to the desired 15 temperature, the invention being of such character as to accomplish the work required in a most efficient manner in a minimum of time, and expense and with practically no loss of whisky. With the above, and other incidental, objects in view, the invention consists 20 of the improved apparatus and its parts, or the equivalents as hereinafter more fully set forth.

In the accompanying drawings illustrating a preferred form of apparatus, Figure 1 is a central, vertical section, parts broken away, of the apparatus as applied 25 to a tank, the tank also being in vertical section; Fig. 2 is a sectional view of the lower part of the apparatus; Fig. 3 is a view of the part shown in Fig. 2 but at right angles thereto, parts broken away; Fig. 4 is a cross section of Fig. 3 taken on line 4-4; Fig. 5 is a 30 cross section of Fig. 3, taken on line 5-5; and Fig. 6 is a cross section of Fig. 3 taken on line 6-6.

The numeral 10 indicates the upper tank of the apparatus, provided in its top with a valve controlled vent tube 11. A steam inlet pipe 12 extends downwardly 35 along one side or end of this tank, and thence beneath the tank to approximately the center of the bottom of the tank, and thence downwardly in a straight line, and a steam outlet pipe 13 extends downwardly along the opposite side or end of the tank and thence beneath 40 the tank to approximately the center of the bottom of the tank, and thence downwardly in a straight line parallel with and adjacent to the corresponding portion of pipe 12. The pipes 12 and 13 are incased by a casing 14, preferably of brass. The lower end of this 45 casing is open, and the upper end thereof terminates in a tapered metallic screw-threaded bung 15. The casing is provided therearound, at a desired distance above its lower end, with a series of apertures 16 arranged annularly, and at a desired distance above 50 the aperture 16 with similarly arranged apertures 17.

The lower ends of pipes 12 and 13 terminate short of the lower end of the casing, and have connection with a hollow block 18 set in the lower end of said casing which block 18 is a return bend, connecting the lower 55 ends of pipes 12 & 13. This block does not fill up the entire bore of the casing, and consequently spaces

19-19 are left on opposite sides of the block, whereby the liquid contents of the receptacle are free to pass into said casing and into spaces 19-19 and out perforations 16-16 and 17-17. Extending from the bottom 60 of the tank 10, and communicating with the interior of said tank, is another pipe 20. This pipe is preferably connected to the bottom of the tank by having its upper extremity which passes through an opening in the tank bottom threaded to receive a nut 21. Pipe 65 20 passes downwardly in a straight line through the bung 15, but on the outside of casing 14, as clearly shown in the drawings, and is considerably shorter than pipes 12 and 13, its lower end terminating but a comparatively slight distance below the lower edge of 70 bung 15, and said lower end being provided with a series of slots 20' in order to insure the provision at all times of free openings to the pipe, even though the lower end of said pipe should become clogged with solid substance, such as shavings, chips, charcoal flakes, and 75 the like.

Fig. 1 of the drawings shows the apparatus applied to a large size tank 22, and Fig. 2 to an ordinary whisky barrel 23. In the application of the apparatus to a tank the several pipes are passed through the bung hole 80 in the upper end or head of the tank, the bung 15 when it reaches the bung hole being screwed tightly into said hole. When the apparatus is thus inserted, the lower end of the casing 14 will be just above the bottom of the tank. The apparatus can of course be applied to a tank of any size by regulating the size of the steam pipes to suit the requirements of different tanks. 85 The apparatus is applied to a barrel in the same manner that it is applied to a tank, excepting that it is inserted through a bung hole in the side of the barrel. 90 As is well known, whisky barrels are made of charred staves, and therefore when my apparatus is applied to a barrel, the charring on the interior of the staves will give the desired color to the liquor. In cases where my apparatus is applied to large size tanks which are 95 not composed of charred staves, I provide charred blocks 24 which float on the surface of the liquid contents, and serve to impart the required color to the liquor.

In the use of the apparatus, the steam admitted 100 through the pipe 12 will flow down said pipe 12 and up and out through pipe 13, as indicated by the arrow in Fig. 5. The course of the steam and heated liquor, as indicated by the arrows in Figs. 1 and 2 of the drawings, develops a complete circulation causing the liquor to 105 move about in the receptacle much the same as a pump would cause the liquor to move. In other words, the cold liquor is caused to go down as indicated by the downwardly pointed arrows in Figs. 1 and 2, to take the place of the hot liquor which is going up through the 110 bottom of the casing and out through the perforations 16 and 17 as indicated by the upwardly pointing ar-

rows in said Figs. 1 and 2. By thus providing for the circulation of heat evenly through the receptacle the gradual heating of the contents is accomplished, and a rush of liquor to and clogging of the outlet pipe, and consequent extra pressure on the receptacle are prevented. This circulating and heating continues until the temperature of every particle is raised to the desired point, without the necessity of raising the temperature to such a high point as to render the liquor bitter. When the temperature of the entire body of liquor is raised to the desired point, the expansion of the liquor causes an increased pressure, and consequently a portion of the liquor is forced up the pipe 20 into the upper tank 10. When the liquor cools down, or when the heating operation is stopped, the liquid in the upper tank will flow back into the lower receptacle.

In addition to the advantages heretofore recited, I claim that with the use of my invention there is practically no loss of whisky, and practically no danger of blowing out the head of the receptacle by pressure, the expansion being so gradual on account of the circulation of the liquor. The heating is also so general that every particle of color is extracted from the stave without raising the temperature to a high point, and that it is capable of accomplishing a most efficient aging of the liquor in a comparatively short space of time, and consequently with a great saving of fuel for steam and labor for operation.

30 While I have described my improved apparatus as particularly adapted for aging whisky, yet I do not wish to be understood as restricting the invention thereto, as it may be employed for the purpose of aging and coloring any other kind of liquor without departing 35 from the spirit and scope of my invention.

What I claim as my invention is:

1. An apparatus for aging liquor, consisting of a tank, an inlet pipe for the heating agent, an outlet pipe for the heating agent, said pipes extending adjacent to each other, and the lower ends of said pipes being connected by a return bend, a casing inclosing the pipes, the lower end of said casing being open, means at the upper end of the casing for engaging the bung hole of a receptacle, and a pipe depending from the tank and extending along the outside of the casing for a desired distance.

40 2. An apparatus for aging liquor, consisting of a tank, an inlet pipe for the heating agent, an outlet pipe for the heating agent, said pipes extending adjacent to each other, and the lower ends of said pipes being connected by a return bend, a casing inclosing the pipes, the lower end of said casing being open and the upper end thereof terminating in a bung, and a pipe depending from the tank and extending through the bung and on the outside of the casing for a desired distance.

45 3. An apparatus for aging liquor, consisting of a tank, an inlet pipe for the heating agent, an outlet pipe for the heating agent, said pipes extending adjacent to each other, and the lower ends of said pipes being connected by a return bend, a casing inclosing the pipes, the lower end 50 of the casing being open, and said casing provided with sets of perforations arranged a desired distance apart, means at the upper end of the casing for engaging the bung hole of a receptacle, and a pipe depending from the tank and extending along the outside of the casing for a desired distance.

55 4. The combination with a receptacle for containing liquor, said receptacle provided with a bung hole, of an apparatus for aging the liquor contained in the receptacle, said apparatus consisting of a tank, an inlet pipe for the heating agent, an outlet pipe for the heating agent, said pipes 60 extending adjacent to each other, and the lower

ends of said pipes being connected by a return bend, a casing inclosing the pipes, the lower end of said casing being open, a pipe depending from the tank and extending along the outside of the casing, and means at the upper 75 end of the casing for engaging the bung hole of the receptacle, when the casing and the inclosed pipes and the depending pipe are inserted through the bung hole, the lower end of the casing when the device is so applied terminating at a desired distance above the bottom of the receptacle.

80 5. The combination with a receptacle for containing liquor, said receptacle provided with a bung hole, of an apparatus for aging the liquor contained in the receptacle, said apparatus consisting of a tank, an inlet pipe for the 85 heating agent, an outlet pipe for the heating agent, said pipes extending adjacent to each other, and the lower ends of said pipes being connected by a return bend, a casing inclosing the pipes, the lower end of the casing being open, and said casing provided with sets of perforations arranged a desired distance apart, a pipe depending from the tank and extending along the outside of the 90 casing, and means at the upper end of the casing for engaging the bung hole of the receptacle, when the casing and the inclosed pipes and the depending pipe are inserted through the bung hole, the lower end of the casing, when the device is so applied, terminating at a desired distance above the bottom of the receptacle.

95 6. The combination with a receptacle for containing liquor, said receptacle provided with a bung hole, of an 100 apparatus for aging the liquor contained in the receptacle, said apparatus consisting of a tank, an inlet pipe for the heating agent, said pipe extending along one side of the tank, thence beneath the bottom of the tank, and thence downwardly, an outlet pipe for the heating agent, said pipe extending along the opposite side of the tank, thence beneath the bottom of the tank, and thence downwardly parallel with and adjacent to the inlet pipe, the lower ends of said pipes being connected by a return bend, a casing inclosing the pipes, the lower end of said casing 105 being open, a pipe depending from the bottom of the tank along the outside of the casing, and means at the upper end of the casing for engaging the bung hole of the receptacle, when the casing and the inclosed pipes and the depending pipe are inserted through the bung hole, the lower end of the casing, when the device is so applied, terminating at a desired distance above the bottom of the receptacle.

110 7. An apparatus for aging liquor, consisting of a receptacle provided with an opening, means inserted through 115 said opening and into the receptacle for heating the liquor contained therein, a casing forming part of said means, and said casing provided with inlet and outlet openings whereby the liquor entering into the casing through the inlet opening is heated to a degree above the temperature 120 of the liquor on the outside of said casing, causing the heated liquor to rise in the casing and to be discharged through the outlet opening, thereby producing a circulation of the liquor within the receptacle.

125 8. The combination with a receptacle for containing liquor, said receptacle provided with a bung hole, charred blocks within the receptacle and adapted to float on the surface of the liquor in said receptacle, of an apparatus for aging the liquor contained in the receptacle, said apparatus consisting of a tank, an inlet pipe for the heating 130 agent, an outlet pipe for the heating agent, said pipes extending adjacent to each other, and the lower ends of said pipes being connected by a return bend, a casing inclosing the pipes, the lower end of said casing being open, a pipe depending from the tank and extending along the outside 135 of the casing, and means at the upper end of the casing for engaging the bung hole of the receptacle, when the casing and the inclosed pipes and the depending pipe are inserted through the bung hole, the lower end of the casing, when the device is so applied, terminating at a desired distance 140 above the bottom of the receptacle.

145 9. An apparatus for aging liquor, consisting of a receptacle provided with an opening, and means inserted through said opening and into the receptacle for heating the liquor contained therein, said means arranged and 150 adapted to heat a column of liquor to a degree above the

- temperature of the liquor adjacent to said column, and to allow said heated column of liquor to flow into the liquor adjacent to said column and thereby produce a rapid circulation of the liquor within the receptacle.
- 5 10. An apparatus for aging liquor, consisting of a receptacle provided with an opening, and means inserted through said opening and into the receptacle for heating the liquor contained therein, means for accommodating the overflow of liquor caused by expansion from heating from the receptacle, said heating means arranged and adapted to heat a column of liquor to a degree above the temperature of the liquor adjacent to said column, and to allow said heated column of liquor to flow into the liquor adjacent to said column and thereby produce a rapid circulation of the liquor within the receptacle.
- 10 11. An apparatus for aging liquor, consisting of a receptacle provided with an opening, means inserted through said opening and into the receptacle for heating the liquor contained therein, means for accommodating the overflow 20 of liquor caused by expansion from heating from the receptacle, a casing forming part of said heating means, and said casing provided with inlet and outlet openings whereby the liquor entering into the casing through the inlet opening is heated to a degree above the temperature of the liquor on the outside of said casing, causing the heated liquor to rise in the casing and to be discharged through the outlet opening, thereby producing a circulation of the liquor within the receptacle.
- 25 12. An apparatus for aging liquor, consisting of a receptacle provided with a threaded opening, and means re-

movably inserted through said opening and into the receptacle for heating the liquor contained therein, said means provided with a threaded portion adapted to engage the threads of the opening and form a liquid tight joint, said heating means arranged and adapted to heat a column of liquor to a degree above the temperature of the liquor adjacent to said column, and to allow said heated column of liquor to flow into the liquor adjacent to said column and thereby produce a rapid circulation of the liquor within the receptacle.

35 13. An apparatus for aging liquor, consisting of a receptacle provided with a threaded opening, and means removably inserted through said opening and into the receptacle for heating the liquor contained therein, said means provided with a threaded portion adapted to engage the threads of the opening and form a liquid tight joint, means for accommodating the overflow of liquor caused by expansion from heating from the receptacle, said heating means arranged and adapted to heat a column of liquor to a degree above the temperature of the liquor adjacent to said column, and to allow said heated column of liquor to flow into the liquor adjacent to said column and thereby produce a rapid circulation of the liquor within the receptacle.
